(57) **CLAIM**

The ornamental design for a sewing machine, as shown and described.

DESCRIPTION

FIG. 1 is a front elevational view of a sewing machine showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view of a sewing machine showing thereof; and,

FIG. 8 is another front perspective view of a sewing machine showing thereof.

1 Claim, 8 Drawing Sheets(56)
